WOVEN PILE FABRIC

Harold E. Wadeley, Irvington on Hudson, N. Y., assignor
to The Firth Carpet Company, Inc., New York, N. Y.,
a corporation of New York

Application June 18, 1954, Serial No. 31,065

Term of patent 14 years

(Cl. D92—4)

To all whom it may concern:

Be it known that I, Harold E. Wadeley, a citizen of the United States of America and a resident of Irvington on Hudson, county of Westchester, State of New York, have invented a new, original, and ornamental Design for a Woven Pile Fabric, of which the following is a specification, reference being had to the accompanying drawing, forming a part thereof.

Referring to the drawing:

The figure is a plan view of a woven pile fabric showing my new design.

The repeatable design unit is outlined by dotted lines as indicated.

I claim:

The ornamental design for a woven pile fabric, substantially as shown and described.
